UNITED STATES PATENT OFFICE.

WOJCIECH BENCZALSKI, OF HOQUIAM, WASHINGTON.

LAUNDRY HANGER.

Application filed March 9, 1922. Serial No. 542,382.

To all whom it may concern:

Be it known that I, WOJCIECH BENCZALSKI, a citizen of Poland, residing at Hoquiam, in the county of Grays Harbor and 5 State of Washington, have invented certain new and useful Improvements in Laundry Hangers; and I do hereby declare the following to be a full, clear, and exact description of the invention, such as will enable 10 others skilled in the art to which it appertains to make and use the same.

The chief intent of the present invention is to improve the structure and arrangement of parts of the appliance forming the subject matter of Patent No. 1,368,383, granted 15 me February 15, 1921.

One of the objects of the present invention is the provision of an improved casing for housing the line reel and the ratchet 20 mechanism cooperating therewith.

Another object of the invention is the provision of novel means for attaching the casing to a wall or like support and which admits of ready detachment thereof when required for any purpose.

The invention also aims to provide line supporting and attaching means of peculiar formation which admits of quickly placing the line in operative position or reeling the 30 same as occasion may require.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a plan section of a laundry or room provided with a clothesline and adjunctive means illustrative of the invention.

Figure 2 is a vertical section of the casing disclosing the enclosed parts and illustrating the supporting means, the parts being shown on a larger scale,

Figure 3 is a fragmentary view of the top of the casing, showing the pawl operating arm,

Figure 4 is a detail view of the means for

securing the outer end of the clothesline when in operative position,

Figure 5 is a horizontal section on the line 5—5 of Figure 2,

Figure 6 is a horizontal section on the line 6—6 of Figure 2, the clothesline being omitted,

Figure 7 is a rear view of the casing,

Figure 8 is a front view of the bracket which is adapted to be attached to a wall or like support for receiving and supporting the casing,

Figure 9 is a sectional detail on the line 9—9 of Figure 5, and

Figure 10 is a perspective view of the link to which the outer end of the clothesline is attached.

Corresponding and like parts are referred to in the following description and designated in the several views of the drawings by like reference characters.

The clothesline 1 is adapted to be wound upon a reel 2 and when extended may be supported in any preferred way substantially as indicated in Figure 1 of the accompanying drawings. A link 3 is secured to the outer end of the clothesline 1 and is provided at one end with an apertured lug 4 through which the end of the line 1 passes and is knotted, as indicated most clearly in Figure 4, to prevent disengagement of the line from the link when attached thereto. The link is contracted at one end, as indicated at 5, whereby to prevent disengagement thereof from anchoring means such as a hook 6 let into the wall and provided with a spool 7. The link 3 since it is applied to the outer end of the line 1, constitutes a stop to limit the winding of the clothesline upon the reel so that the outer end may be conveniently grasped when it is required to extend the line for service.

Opposite walls 9 of a laundry or room are provided with hooks 6 at the required elevation for receiving and supporting the clothesline 1, the latter when extended occupying a zigzag arrangement, as indicated most clearly in Figure 1. Each of the hooks 6 is provided with a spool 7 to admit of free play of the line, whereby to equalize the strain thereon and prevent unnecessary wear upon the line. The casing containing the reel is preferably located adjacent a corner

of the room and the anchoring hook for the outer end of the clothesline is located at a remote corner of the room, thereby admitting of the line when extended being arranged substantially as indicated in Figure 1.

The casing comprises a back 10, sides 11, bottom 12, top 13 and front 14. The back, sides, bottom and top preferably constitute parts of a single sheet metal blank, whereas the front 14 is separate and secured to the forward edges of the sides 11 in any preferred way, preferably by having the opposite vertical edge portions bent substantially as indicated in Figures 5 and 6 and electrically welded to the inner faces of the side walls. The inner flanges 15 at the vertical edges of the front 14 are inset the thickness of the sides 11, whereby the outer faces of the sides 11 and the folded edges of the front 14 are about flush. The rear edges of the sides 11 and top 13 are flanged, as indicated at 16, to overlap the outer or rear side of the back 10 to which they are electrically welded or made secure in any preferred way. The enclosing walls, with the exception of the front 14, are flat, whereas the front 14 is forwardly curved between its top and bottom edges and has its upper portion cut away to provide an opening 17 which is closed by means of a swinging door 18. The door 18 is of such length so that when closed, a transverse opening is provided for the passage of the clothesline 1, as indicated most clearly in Figure 2. The lower edge of the door 18 and the edge of the front 14 bordering upon the lower part of the opening 17 are thickened to prevent injurious contact with the line 1 as the same is wound upon the reel 2 or unwound therefrom. The door 18 admits of ready access to the interior of the casing and its lower end readily adapts itself to the position of the line 1 when extended and under tension.

Similar upper and lower brackets 19 are attached to the back 10 of the casing and each includes a depending stud 20 which is centrally disposed and of non-circular form so as to prevent any swinging movement of the casing when attached to the wall 9 or other support. The brackets 19 may be of any construction but are preferably formed of sheet metal which is fashioned into the shape substantially as shown. The studs 20 are adapted to enter keepers 21 carried by a plate 22 which is formed with openings to receive screws 23 or like fastenings whereby the plate 22 is adapted to be attached to the wall 9 or other supporting means. The plate 22 and keepers 21 constitute parts of a wall bracket to which the casing is adapted to be detachably connected.

The reel 2 is journaled at its ends in brackets 24 secured to the back 10 of the casing and disposed within the latter. One end of the reel shaft projects beyond a side of the casing and is adapted to have a crank handle 25 applied thereto for convenience of rotating the reel to wind the clothesline 1 thereon. A ratchet wheel 26 is fast to an end of the reel 2 and cooperates with a pawl 27 pivoted to a bracket 28 attached to the rear wall 10 of the casing. Backward rotation of the reel is prevented by the ratchet wheel 26 and pawl 27, thereby preventing the unwinding of the clothesline 1 therefrom after being extended and properly arranged for supporting articles to be aired and dried. The pawl 27 is adapted to be manipulated by means of an arm 29 which is pivoted at its lower end thereto, the upper end of said arm extending through a slot 30 formed in the top 13 of the casing, one end of the slot 30 being contracted, as indicated most clearly in Figure 3, whereby to support the arm 29 and pawl 27 when the latter is disengaged from the ratchet wheel 26 to admit of the line 1 being readily drawn from the reel when extending and arranging the same for service. The upper end of the arm 29 is enlarged to provide a fingerpiece and lateral shoulders 31 which engage portions of the top 13 bordering upon the contracted portion of the slot 30, whereby to support the arm 29 when lifted to disengage the pawl 27 from the ratchet wheel 26. Projections 32 at the inner end of the contracted portion of the slot 30 are adapted to engage the lateral shoulders 31 of the arm 29 and retain the latter in elevated position against possible displacement. An element 29 is carried by the reel 2 to permit the inner end of the clothesline 1 to be secured to the reel.

What is claimed is:

In a laundry hanger, a casing for receiving a clothesline reel, the same having its front forwardly curved between its upper and lower edges and having an opening in the upper portion thereof, and a door for closing said opening hinged at its upper edge and adapted to swing outwardly at its lower edge and of less length than the opening so that when closed an opening is provided for the passage of the clothesline, the edge portions of the door and front bordering upon the clothesline opening being thickened to prevent injurious contact with the clothesline.

In testimony whereof I affix my signature in presence of two witnesses.

WOJCIECH BENZALSKI.
